RAIL ANCHOR

John J. Gallagher, Denver, Colo., assignor, by
mesne assignments, to Poor & Company, Chi-
cago, Ill., a corporation of Delaware

Application June 29, 1946, Serial No. 680,452

9 Claims. (Cl. 238—329)

1

This invention relates to improvements in rail anchor devices for resisting longitudinal movement of railroad rails and particularly to devices of this character in which a U-shape jaw member grips one flange of a rail base and a retaining device therefor is driven transversely through the jaw member into locking engagement with the rail base flange at the other side of the rail.

A principal object of the invention is to provide a rail anchor of the above general class which has a U-shaped jaw member formed to grip one base flange of a rail and is offset to overlie the top surface of a crosstie so as to bear against an edge of a tie plate supported on the crosstie and spaced inwardly from the vertical face thereof.

Another important object of the invention is to provide a two-piece anchor device of the above general type having a U-shaped jaw member, one vertical arm of which is off-set in a direction lengthwise of the rail and thereby provides a construction which cooperates with the retaining member, when the latter is forced to its applied position, to develop a lateral pressure component which is exerted against the other arm of the U-shaped jaw member to press the rail gripping surfaces thereof into increased holding engagement on the rail.

Another and more specific object of the invention is to provide, in a rail anchor of the above general class, an improved U-shape jaw member having spaced apart arms which are recessed to receive one edge of a rail base; the recess in one arm of the jaw member being formed to provide a firm non-resilient grip on the top and bottom of the rail base and the other arm being recessed and off-set laterally, whereby the off-set portion of the arm provides the U-shaped member with sufficient resilience, when the anchor device is applied on a rail, to absorb or cushion vibration and other forces which tend to loosen the grip of the U-shaped jaw member on the rail.

One specific form of the invention is illustrated in the accompanying drawings wherein:

Fig. 1 is a view partly in section and partly in elevation illustrating the construction of the improved rail anchor device applied to the base portion of a railroad rail in a position to abut against a stationary part of the roadbed.

Fig. 2 is a fragmentary plan view of the structure shown in Fig. 1.

Fig. 3 is a sectional view taken on line 3—3 of Fig. 1 looking in the direction indicated by the arrows so as to illustrate the manner in which one arm of the jaw member is offset to overlie the top surface of a crosstie.

Fig. 4 is a fragmentary sectional view taken on line 4—4 of Fig. 3.

Fig. 5 is a view in perspective of the jaw mem-

2

ber illustrated in Figs. 1 to 3 inclusive of the drawings.

Fig. 6 is a fragmentary view in side elevation of one side portion of the jaw member to illustrate a slit 27 formed therein and also showing the position of the lower jaw portion 25 before the latter is bent laterally to the position shown in Figs. 4 and 5.

Referring now to the drawings: 10 designates 10 the base portion of a railroad rail, 11 an ordinary wood crosstie on which the rail is supported, and 12 is a tie plate interposed between the base portion of the rail and the top surface 13 of the crosstie.

15 The tie plate is formed with spaced shoulders 14 and 15 which provide lateral abutments for the opposite edges of the rail base. The width of the tie plate 12 is preferably less than the width of the crosstie 11, and therefore is spaced 20 inwardly from the plane of the vertical face 14^a of the crosstie in Figs. 2 and 3 of the drawings. The tie plate 12 may be secured to the crosstie by any suitable means. For convenience of illustration, the fastening means herein shown consists of a plurality of spikes 16 adapted to be driven into the wood crosstie through openings 17 formed in the tie plate. The head of the spike projects over the upper surface of the rail base flange so as to maintain the rail in its normal 25 position on the tie plate. Preferably there is a slight clearance 18 between the under surface of the spike head and the top surface of the rail base flange so as to permit normal vertical movements of the rail relative to the tie plate.

30 35 The rail anchor device may be briefly described as comprising a U-shape jaw member 19 and a separately formed retaining member 20. The latter engages the jaw member and the opposite edge of the rail base to hold the jaw in its applied position. The jaw member is formed by bending a metal strip into a U-shape configuration so as to provide spaced arms 21 and 22. The arms are provided with recesses 23 and 24 adapted to fit the edge portion of one flange of the rail base. The arm 21 of the jaw member is preferably 40 flat and the recess 23 therein is formed to fit the rail flange tightly when the jaw device is driven transversely of the rail to its applied position. The upper and lower surfaces 23^a and 23^b 45 of the recess 23 are directly opposed to each other and are confined to the thickness of the arm 21. The said upper and lower surfaces, therefore, exert a rigid grip on the rail base when the anchor jaw is driven to its applied position on the rail.

50 55 The other arm 22 of the jaw member is formed with a lateral off-set 25 and the end 26 of the arm is turned upwardly at right angles to the lateral off-set portion. The recess 24, formed in this arm fits loosely over the rail base, but there 60 is a resilient binding engagement between the

bottom surface 24^a and the surface 24^b of the lateral offset portion when the anchor jaw is driven onto the rail. In order to permit the arm 22 to be bent quite sharply along the lower edge of recess 24, the metal at the end of the recess is slit vertically at 27, as shown best in Figs. 3, 4, 5 and 6, so that the off-set portion 25 can be positioned in close relation to the bottom surface of the rail and the portion thereof designated 24^b will engage the bottom surface of the rail base and constitutes the lower gripping surface of the arm 22. In Fig. 6, the said slit 27 is shown in connection with the portion 25 before the latter is bent to the lateral portion shown in Figs. 4 and 5. The fact that the recess 24 includes the slit 27 makes it possible to confine the bend 25^a to the portion of the arm 22 which intervenes between the slit 27 and the outer edge of said arm (see Figs. 4 and 5). It will be observed also, that the relatively narrow recess 24, as shown in Fig. 6, is increased to the proper width to receive the rail base flange, when the portion 25 assumes its lateral position relative to the vertical portion of the arm 22.

The recesses 23 and 24 extend inwardly from the inner vertical edges of the jaw arms at an angle whereby the jaw member, when applied to a rail, will assume the angular position shown in Figs. 1 and 3, consequently the bottom 28 inclines upwardly and inwardly toward the longitudinal center of the rail base to provide a wedge shape space between the bottom surface of the rail base and the bottom 28 of the U-shaped jaw member. The bottom 28 may also be provided with an up-pressed corrugation 29 to provide an outer bearing surface for the retaining member 20.

The retaining member 20 comprises a spring metal strip formed at one end with a return bend which forms a wedge shaped loop 30. This loop fits into the angular space between the bottom of the rail base and the bottom portion 28 of the jaw member. The other end of the retaining member 20 is formed with an upturned portion 31 which engages over the lower corner portion 32 of the rail base flange. The up-turned portion 31 and the wedge shaped loop 30 serves to hold the anchor jaw 19 firmly on the rail.

The anchor device is applied to the rail by fitting the recesses 23, 24 of the jaw member over one edge of the rail base in a position whereby the flat outer face of the lower portion of the arm 22 will bear against the vertical face 13^a of cross-tie 11 and the off-set portion 25 will overlie the top surface of the cross-tie and bear against a vertical edge portion of the tie plate 12. The jaw member is then driven transversely of the rail to cause the opposed surfaces 23^a and 23^b of the arm 21 and the surface 24^a and 24^b of the off-set arm 22 to grip the top and bottom surfaces of one base flange of the rail. The retaining member 20 is then driven transversely of the rail through the U-shaped jaw member 19 until the up-turned portion 31 of the retaining member snaps up over the lower corner 32 of the rail base flange at the other side of the rail. By forcing the wedge shaped loop 30 into the space between the bottom surface of the rail base and the bottom portion 28 of the jaw member 19, vertical pressure is exerted between the said bottom surface of the rail base and the bottom 28 of the jaw member.

The off-set arm 22 of the jaw member is sufficiently flexible to permit slight downward movement thereof relative to the arm 21 when the retaining member loop 30 is driven to its applied

position. As a result of this condition, a lateral pressure component is developed and exerted against the arm 21 in the direction indicated by the arrow A, whereby the corner portions 33, 34 of the recess 23 are pressed more firmly against the top and bottom surfaces of the rail base flange. This increased gripping action is further increased by any pressure of the arm 22 against a side face of a cross-tie. The off-set configuration of the said arm 22 of the jaw, in addition to providing the flexibility and resilience for effecting said increased gripping action, also provides resilience to take up any looseness in the fit of the jaw member on the rail which may result from wear due to vibration or other causes encountered in service.

While the invention is illustrated in connection with one specific embodiment, it will be obvious from the disclosures herein that the principles of the invention may be applied to other rail anchor devices of similar form. It will be understood, therefore, that the embodiment herein shown is intended merely as a convenient illustration and not as a limitation.

I claim:

1. A rail anchor for resisting lengthwise creep of a railroad rail relative to a cross-tie on which the rail is supported, comprising a jaw member for gripping one base flange of the rail, and a retaining member movably engaged with the jaw member and having an upstanding portion for locking engagement with the other base flange of the rail to hold the jaw member in its applied position; the said jaw member including spaced apart vertical arms each formed with a recess to provide surfaces for gripping the top and bottom surfaces of one base flange of the rail and one arm of said jaw member being formed with a vertical surface for engaging a vertical side face of the cross-tie and with a laterally extending portion adapted to overlie the top surface of said cross-tie.

2. A rail anchor for resisting lengthwise creep of a railroad rail relative to a cross-tie on which the rail is supported, comprising a jaw member for gripping one base flange of the rail, and a retaining member movably engaged with the jaw member and having an upstanding portion for locking engagement with the other base flange of the rail to hold the jaw member in its applied position; the said jaw member including spaced apart vertical arms each formed with a recess to provide surfaces for gripping the top and bottom surfaces of one base flange of the rail and one arm of said jaw member being adapted to bear against a vertical face of a cross-tie and laterally off-set to provide a portion defining the lower surface of the recess in the arm and extending longitudinally beneath the rail and overlying the top of the cross-tie.

3. A rail anchor comprising a jaw member for gripping one flange of a rail base and for abutting against a stationary part of the roadbed on which the rail is supported, and a retaining member movably engaged with the jaw member and having means for engaging the other base flange of the rail to hold the jaw member in its applied position; the said jaw member comprising a U-shaped device having spaced apart vertical arms each formed with a recess to provide surfaces for gripping the top and bottom surfaces of the first mentioned base flange of the rail and one arm only of the jaw member being offset in a direction lengthwise of the rail to provide resilience so that this arm of the jaw member will yield, when

the jaw member is pressed against said stationary part of the roadbed and thereby permit the rail gripping surfaces of the other arm to exert a shackle grip on the top and bottom surfaces of the rail base.

4. A rail anchor comprising a jaw member of U-shaped configuration having spaced apart upwardly extending arms and each having a recess providing spaced rail gripping surfaces adapted to be forced into firm gripping engagement with the top and bottom surfaces of one base flange of the rail base, and a retaining member formed at one end with a general wedge shaped portion adapted to be driven into firm wedging position between the lower surface of the rail base and a portion of the jaw member and formed at its other end with means for locking engagement with the other base flange of the rail; one arm only of the jaw member being laterally off-set to provide resilience and adapted to yield under the wedging pressure exerted by said retaining member to exert a resilient grip on the top and bottom surfaces of the rail base and to exert turning pressure on the opposed rail gripping surfaces of the other arm of the jaw member to force them into shackle gripping engagement with the top and bottom surfaces of the rail base flange on which the jaw member is applied.

5. A rail anchor for resisting longitudinal creeping movement of a railroad rail relative to a cross-tie and a tie plate on which the rail is supported, comprising a jaw member for gripping one base flange of the rail, and a retaining member having a return bend which forms a resilient wedge at one end movably engaged with the jaw member and having an upstanding portion at the other end for locking engagement with the other base flange of the rail to hold the jaw member in its applied position; the said jaw member including spaced apart vertical arms each formed with a recess to provide surfaces for gripping the top and bottom surfaces of one base flange of the rail and one arm of said jaw member being adapted to bear against a vertical face of the cross-tie and laterally off-set to provide a portion defining the lower surface of the recess in the arm and which extends longitudinally beneath the rail and overlies the top of the cross-tie for an abutting engagement with said tie plate supported thereon.

6. A rail anchor comprising in combination, a jaw member having a bottom portion connecting spaced vertically extending arms formed with aligned recesses each having opposed surfaces adapted to be driven into tight gripping engagement with the top and bottom surfaces of one base flange of the rail and one arm only of the jaw member being laterally off-set to form a portion providing a flat surface defining the lower surface of the adjacent recess, and a retaining member wedged between the bottom face of the rail base and said bottom portion of the jaw member, whereby the lateral off-set of said arm is flexed downwardly to increase the effective length of the arm and thereby exert resilient lateral pressure against the other arm to increase the grip of said opposed surfaces on the rail.

7. A rail anchor comprising in combination, a jaw member having a bottom portion connecting spaced vertically extending arms formed with aligned recesses each having surfaces adapted to be driven into tight gripping engagement with the top and bottom surfaces of one base flange of the rail and one arm only of the jaw mem-

ber being off-set laterally adjacent its recess to provide a portion overlying the top surface of an adjacent crosstie, whereby a portion of the off-set arm is adapted to bear against a vertical face of said crosstie and this said off-set portion is adapted to abut against a tie plate supported on the crosstie, and a retaining member formed with a return bend to provide a wedge shaped loop adapted to be wedged between the bottom face of the rail base and said bottom portion of the jaw member, whereby the lateral off-set of said arm is flexed downwardly to increase the effective length of the arm and thereby exert lateral pressure against the other arm to increase the grip of said opposed surfaces on the rail.

8. A rail anchor comprising in combination, a jaw member having a bottom portion connecting spaced vertically extending arms formed with aligned recesses and provided with surfaces adapted to be driven into tight gripping engagement with the top and bottom surfaces of one base flange of the rail and one arm only of the jaw member being off-set laterally adjacent its recess to provide a portion overlying the top surface of an adjacent crosstie, whereby a portion of the off-set arm is adapted to bear against a vertical face of said crosstie and this said off-set portion is adapted to abut against a tie plate supported on the crosstie, and a retaining member formed with a return bend to provide a wedge shaped loop adapted to be wedged between the bottom face of the rail base and said bottom portion of the jaw member, whereby the lateral off-set of said arm is flexed downwardly to move the opposed surfaces of the off-set arm into tighter spring engagement with the rail base and to increase the effective length of the arm and thereby exert lateral pressure against the other arm to increase the grip of said opposed surfaces on the rail.

9. A rail anchor comprising in combination, a jaw member having a bottom portion connecting spaced vertically extending arms formed with aligned recesses and provided with surfaces adapted to be driven into tight gripping engagement with the top and bottom surfaces of one base flange of the rail and one arm only of the jaw member being off-set laterally adjacent its recess to provide a rail gripping portion substantially wider than the thickness of the arm which portion overlies the top surface of an adjacent crosstie, whereby a portion of the off-set arm is adapted to bear against a vertical face of said crosstie and this off-set portion is adapted to abut against a tie plate supported on the crosstie, and a retaining member wedged between the bottom face of the rail base and said bottom portion of the jaw member, whereby the lateral off-set of said arm is flexed downwardly to increase the effective length of the arm and thereby exert resilient lateral pressure against the other arm to increase the grip of said opposed surfaces on the rail.
